CLOSURE CAP FOR RECEPTACLES
AND BOTTLES

William T. McHaffey, Brooklyn, N. Y.

Application March 22, 1935, Serial No. 12,467

3 Claims. (Cl. 116—121)

This invention relates to new and useful improvements in closure caps for receptacles, such as bottles, and it has more especially for its object to provide a bottle cap in combination with a timing device for use in connection with medicine bottles, whereby the important work of a nurse attending a patient may be considerably facilitated, and at the same time greater accuracy assured, as to the dispensation of medicine to the patient as the timing device embodied in said bottle cap will make it possible for a nurse always to adjust, or set the device ahead for the exact hour, when the next dose of medicine is to be given to a patient, thereby avoiding forgetfulness, or irregularity in this respect on the part of the nurse.

As the construction of my device is comparatively simple, the cost of manufacturing should be proportionately low.

With the above and other objects in view, this invention consists of the novel features of construction, combination and arrangement of parts, hereinafter fully described, claimed and illustrated in the accompanying drawing forming part of this specification, and in which similar characters of reference indicate corresponding parts in all views, and in which:—

Figure 1 is a perspective view of my device mounted on a bottle.

Figure 2 is a top plan view of said device.

Figure 3 is a vertical transverse sectional view through my device, and the neck of a bottle.

Figure 4 shows a vertical transverse sectional view through the bottle cap proper. Figure 5 illustrates a slight modification of my device. Figure 6 is a top plan view of the modified construction shown in Figure 5; while Figure 7 shows a vertical transverse sectional view of said modification. Figure 8 shows my device attached to a chart. Figure 9 illustrates my device modified as to the time-indicating means; while Figure 10 is a vertical transverse sectional view of my device, as shown in Figure 9. Figure 11 shows my watch-device displayed upon a circular surface

45 suitable for attachment to an object. Figure 12 is a transverse sectional view of a further modification of a cap-member embodying my device. Figure 13 is an elevational view of the movable rim, relative to same, showing a cut out portion 50 therein. Figure 14 shows a plan surface of a disk member forming part of said device, the revolvable rim being removed. Figure 15 is a somewhat perspective top plan view, showing another slight modification of my said device, substantially along 55 the principles disclosed in the views 12, 13, and

14; while Figure 16 is a somewhat perspective view of a disk member, or lower part of my device, with the revolvable rim portion removed.

Referring more particularly to the drawing, 10 indicates a bottle cap made of any suitable material, such as metal, glass or bakelite. The said bottle cap, which, if desired, may be screwthreaded, as shown at 11 in Figure 3, serves the conventional purpose of a stopper relative to a bottle, and it is especially thought to be of great value 10 when used as a closure-means for a medicinal bottle or receptacle. The said bottle cap is upon its top formed with a circular depression 12, while time-indicating numerals 1 to 12 are marked or imprinted upon the top surface 13 of the flange, 15 which surrounds the said depression 12. Conventional watch-pointers 14 and 15 are secured to the bottom of the depressed area 12 by means of a pivot 17, or in any suitable manner.

The said depressed area may be either of a 20 concave or convex form, with the pointers correspondingly bent. Thus, as has been shown in Figure 4, the said depressed bottom 12 is slightly convex with the ends of the pointers 14 and 15 bent slightly downwardly, which arrangement 25 protects the said pointers from bending in shipment.

It will be evident that the said bottle cap, as a sheer novelty, will afford excellent advertising space upon the side thereof, and also upon the 30 depressed area.

In Figure 5 is shown a modification of my device to the effect that the said bottle cap may be secured to a bottle or receptacle by means of the fangs or depending portions 16 being clamped on 35 to the bottle neck; said depending portions are formed in one piece with the cap proper, which in this instance would be made preferably of metal; said depending portions naturally would allow for further advertising space. 40

The said cap, with its characteristic top portion, may also be formed with a flat bottom, and secured to a cardboard, or package, as shown especially in Figure 8.

In Figures 9 and 10 a further modification of 45 my device has been shown to the effect that the depressed area 12 herein has been formed with two concentric grooves 18 and 19, each of a substantially circular shape in cross-section. The distance between the edges of the upper or open 50 portion of the said grooves is, however, slightly smaller than the diameter of said grooves, which arrangement serves the purpose of holding in place within said grooves two ball-members, only one of which the ball member 20 may be seen in 55

the drawing, and which balls are made of a somewhat springy material so that they may be snapped into said grooves in which they are otherwise adapted to move comparatively freely.

- 5 To said balls are integrally attached upright pins, one of which may especially be seen at 22, and to said pins are in turn integrally secured short triangular pointers 23 and 24, adapted to register with and indicate the timing relative to 10 the numerals arranged as described before upon the flanges surrounding the depressed area, but which numerals may also be imprinted upon the depressed area itself.

15 In Figure 11 the time-indicating means is shown arranged upon a circular member 25, with plenty of space for advertising, said member may in turn in a label-like manner be attached to a package, or receptacle.

20 In Figure 12 is shown a transverse section of a modification of the cap member, to the effect that the rim portion 26 is revolvable with respect to the other part of the cap member, the rim may be attached to the said other part in any suitable way, for instance by having its flanges bent, as shown at 27, and snapped into a slight recess 28 formed upon said other part; the rim is upon its top made with a slight cut-out portion 29 in order that, when said rim is revolved, the 25 numerals, as shown in Figure 14, at the periphery of the other part of the cap member, may then be visible through said cut-out portion in the rim, and the latter thus adjusted to indicate the desired time.

30 In the Figures 15 and 16 a somewhat similar arrangement has been made. In these modifications the numerals are, however, upon the top of the rim, as shown at 30, whereas a pointer is arranged upon the disk, as shown at 31, for cooperation with said numerals. The rim revolves upon the other or lower part of the cap member, as it is held in position by means of a stud 32 formed upon the latter; this stud is adapted to fit an opening 33 in the rim, as the latter is 35 mounted upon said other part of the cap member, a slight convex enlargement may be formed upon the rim along the side thereof, as shown at 40

34, to accommodate said stud during the revolving motion of the rim.

This latter arrangement may, however, be subject to varied changes.

It is obvious that changes may be made in the 5 form, construction and arrangement of the several parts, as shown, within the scope of the appended claims, without departing from the spirit of the invention, and I do not therefore wish to limit myself to the exact construction and arrangement shown and described herein.

What I claim as new, and desire to secure by Letters Patent of the United States, is:—

1. In a device of the class described, a closure cap for receptacles, bottles, and the like, said 15 closure cap being formed with a central depression at its top, two concentric grooves arranged in said depressed area, time-indicating numerals arranged at the periphery of the cap, and means movably mounted in each of said grooves, and 20 adapted to cooperate with said time indicating numerals.

2. In a device of the class described, a closure cap for receptacles, bottles, and the like, said 25 closure cap being formed with a central depression at its top, two concentric grooves arranged in said depressed area, ball members mounted in said grooves, respectively, and having an upright integral therewith, pointers secured to said uprights, and time indicating numerals arranged 30 at the periphery of the cap and adapted to operate with said pointers.

3. In a device of the class described, a closure 35 cap for receptacles, bottles, and the like, said closure cap being formed with a circular depression at its top, a rim surrounding said depression, two concentric grooves formed in said depression and being of a substantially circular shape in cross-section, triangular time-indicating pointers secured to pins, the latter being mounted upon 40 balls, respectively, said balls being adapted to move in the grooves and to be retained by the latter, and time-indicating numerals arranged upon the top-surface of the rim portion for cooperation with said pointers, substantially as shown 45 and described.

WILLIAM T. MEHAFFEY.
